CLAIM

I claim, the ornamental design for an LED housing, as shown and described.

DESCRIPTION

FIG. 1 illustrates a perspective view of a LED housing, comprising a new design; and,

FIG. 2 is an enlarged cross-sectional view taken from the cut line 2-2 in FIG. 1 thereof.

The break lines in FIG. 1 indicate that the appearance of any portion of the LED housing between the break lines forms no part of the claimed design.
